UNITED STATES PATENT OFFICE.

OLE A. MELANG, OF SEATTLE, WASHINGTON.

STAVE-FINISHING MACHINE.

Application filed August 12, 1924. Serial No. 731,546.

My invention relates to machines for finishing staves.

The object of my invention is to provide a machine which at one time will chamfer and croze the ends of the staves and sand paper the two faces thereof.

My invention consists, essentially, in the peculiar constructions employed for doing this work.

10 The novel features of my invention will be hereinafter described and then specifically set forth in the claims.

The accompanying drawings show my present method of constructing the machine.

15 Figure 1 is a side elevation of the machine with portions of the supporting frame in section.

Figure 2 is a plan view of the same machine with a portion of the upper part of 20 the frames in section and removed.

Figure 3 is an end view of the machine with portions of the frame in section.

25 Figure 4 is a detail showing of an edge view of one of the cutters employed for finishing the ends of the staves.

This machine is intended for operating upon staves which have been sawed out of transversely curved shape to conform to the curvature of the finished keg or barrel and 30 with their edges jointed, that is, beveled and shaped to the form of the finished stave. While it is preferred to have the latter operation, namely the shaping of the edge surfaces of the stave, performed before finishing 35 in the machine which forms the present invention, it is evident that the order may be changed so as to have this particular part of the manufacturing operation performed after the stave has been treated by the present machine.

40 A shaft 1 is supported in suitable bearings and has thereon a pair of feeding wheels 10 which are designed to engage the two ends of the staves and feed them to and past the end of the finishing cutters and the sanding drum which surfaces one face thereof. This shaft 1 is shown as journaled in 45 hangers 11 which depend from a member of the frame. It is driven through the action of a pulley 12 carried by the shaft 1 and a belt 13 running thereon, from any suitable 50 source of power.

55 A transverse member 20 of the general frame 2 extends beneath the feed wheels 10 and has a concave curved section 21 concentric in curvature with the center or the

shaft 1. This forms a guideway over which the staves are moved while being operated upon by the end-finishing cutters and the sanding drum. To insure a positive feed of 60 the staves and also to maintain them with certainty in directions which extend truly lengthwise of the cylinder outlined by the feeding drums, I prefer that the feeding drums 10 be provided with pins or projections 14 of less length than the thickness of the staves. Staves are fed to the feeding drum by hand, and occupy the space between successive pins or projections 14. These engage the edges of the staves and insure that they pass through the machine in 65 correct position.

Two end-finishing mechanisms, essentially the same, are provided, one for each end of the stave, and these operate simultaneously 70 upon the opposite ends of the same stave. Such finishing mechanisms consist of a cutter head 3 having suitable knives thereon mounted upon a shaft 30 which is journaled in bearings 31 at each end of the frame. The cutter head is provided with a cutting-off saw 32 at one side thereof. Next to this is a coned section 33 having adjustable blades adapted to form the bevel or chamfer 75 at the end of the stave. This blade is also preferably provided with a short section 34 which is designed to dress a cylindrical surface, and next to this are cutting blades 35 which form the croze or groove in which the edges of the barrel head are placed. It is 80 evident that all of these cutters may be made to finish the stave in any shape and pattern desired. The particular shape and pattern of this cutter shown in the drawings is only given as an illustration of a cutter intended 85 for finishing the ends of the staves in a particular manner. It is desirable, however, in order to insure uniformity of the staves, and the same relationship between the several cuts, that they all be performed at the same 90 time by the single cutter head.

It is essential that the depth of the croze be uniform, not so much with respect to the inner surface of the stave, as with respect to its outer surface, for the assembling of the 105 barrel, and consequently the lining up of the width and depth of the crozes in adjacent staves, is controlled altogether by the engagement of hoops with the outside of the staves. I have found that the only way in 110 which uniformity of the croze with respect to the outside surface of the barrel can be

secured is to finish this outside surface of the stave, as by sanding, at the same time the crozing is done, and while the crozing cutters are engaging the stave. First finishing 5 the outside, and then crozing the stave will produce only approximate results for the reason that in shifting position between two separate stations where the stave is to be operated upon, the stave is bound to be shifted somewhat, however slight, relative to its carrier, and thus a variation between the outside and the bottom of the croze will result. Further, this necessitates another operation, involving the employment of another operator and another machine and the investment and operation cost of the second machine. First crozing the stave and then sanding it on the outside is worse, for this cannot possibly produce a uniform stave such 20 as is required in tight barrels.

For the purpose, then, of securing absolute uniformity of the staves, assuring exact conformity of their crozes when their outer surfaces conform, and eliminating so far as possible, investment in materials and cost of power and labor, I provide a sanding roller or drum 4, positioned to engage the outer surface of the stave as it passes under the cutter heads 3, the operation of the cutter 25 heads and sander being simultaneous. This sanding drum 4 may be journaled in the frame, its shaft 40 being provided with a pulley 41 by which it is turned.

As the staves are delivered from the feeding 35 disks or drum 10 they are received upon a conveyor, herein illustrated as an endless chain or belt 5 which passes over sprocket gears 50 and which is provided with upward projections or lugs 51 which engage with 40 the edges of the staves and carry them beneath a sanding drum 6, which sands the upper or concavely curved face of the staves. The exact relationship between the bottom of 45 the croze and the outer surface of the stave having previously been secured, it is not essential that the depth of the croze relative to this inner surface be exact.

By the use of this device both ends of the staves are completely finished and the two

major faces are also sanded. Each and every stave is therefore a duplicate of the other staves in this respect. They may thus be assembled after complete finishing with a certainty that they will fit in place, and with the certainty that, when hoops cause 55 their outer surfaces to coincide, the crozes will align in height and depth, to receive the circular heads.

What I claim as my invention is:

1. A stave finishing machine comprising 60 means for feeding the staves transversely of their length, a revolving cutter engaging each end of the staves as they are advanced by the feeding means to thereby chamfer and croze the staves, and a sander engaging the 65 outer face of the stave during their engagement by said cutters.

2. A stave finishing machine comprising 70 means for feeding the staves transversely of their length, revolving cutters positioned to engage the opposite ends of a stave simultaneously as it is advanced by the feeding machine, thereby to croze the inside of the staves, and a sanding device positioned to engage the outside of the stave, substantially 75 throughout its length, during its engagement by said cutters.

3. In a stave finishing machine, a curved guide, a substantially straight guide forming a continuation thereof, a pair of end-finishing cutters rotatable concentrically with said curved guide, means for advancing individual staves in a direction transversely of their length over said guides and past said end-finishing cutters, whereby both ends are finished simultaneously, a transversely extending rotary sander positioned to engage the entire length of a stave during its engagement by said end-finishing cutters to finish its outer surface, and a second transversely extending rotary sander positioned above said straight guide to engage the inner surface of a stave from end to end after its release from said first sander and said end-finishing cutters. 85 90 95

Signed at Seattle, King County, Washington, this 12th day of July, 1924.

OLE A. MELANG.
